AIRPORT BOUNDARY LIGHT

Thomas W. Rolph, Newark, Ohio, assignor to
Holophane Company, Inc., New York, N. Y., a
corporation of Delaware

Application August 1, 1931, Serial No. 554,466

3 Claims. (Cl. 240—1.2)

The present invention relates to airport boundary lights and is more particularly directed toward such lights designed to give a signal to the aviator distant from the landing field and at an elevation suitable for gliding to a landing.

5 The present invention contemplates a boundary light employing a single concentrated light source and a glass enclosure for the light source adapted to concentrate substantially all of the light rays into a primary signalling beam extending upwardly at a slight angle above the horizontal and a secondary beam projected downwardly for downward illumination of objects underneath the luminair, more especially for the illumination for a boundary cone. The boundary lighting luminair contemplated by the present invention is one which obtains the primary beam by means of a prismatic refractor preferably with a wide vertical angle of acceptance and arranged to send out the light in an upwardly inclined beam at an angle to the horizontal substantially that of the gliding angle of an airplane, or at an angle of from 4° to 12° above the horizontal.

10 A further object of the invention is to provide an outdoor lighting luminair with a refractor designed to give the desired signal and having a smooth outer surface, preferably provided by a totally enclosing envelope of pressed or blown glass which protects the refractor. This envelope 15 may be of clear or colored glass, depending upon the color of light desired, and when the colored glass is employed in the envelope instead of in the refractor, it is possible to obtain more uniform color value and hue in the emitted beam. A further object of the invention is to design the luminair so that the glass parts may be preassembled as a unit which may be placed on the support or removed from it without disassembling the glass.

20 The accompanying drawing shows, for purposes of illustrating the present invention, several embodiments in which the invention may take form, it being understood that the drawing is illustrative of the invention rather than limiting the same.

In this drawing:

25 Fig. 1 is a side elevational view of a complete boundary lighting unit illustrating a luminair and boundary cone;

30 Fig. 2 is a vertical sectional view through one form of boundary light;

35 Fig. 3 is a fragmentary sectional view through the lower portion of a modified form of boundary light of the type shown in Fig. 2; and

Figs. 4 and 5 are vertical sectional views illustrating other modified forms of construction.

In the drawing the support for the boundary light is indicated in a form of metal fitter 10 having an internally threaded hole 11 by which it may be mounted on an upright support. The fitter 10 has an internal flange 12 located below internal threads 13 adapted to receive the glass part. A lamp socket 14 is secured to the flange 12 either directly as shown in Fig. 5 or by means of a 10 bridging member 15 as indicated in Figs. 2 and 3. The lamp socket 14 supports a lamp bulb 16 having a concentrated light source L. Where the unit is for use with boundary cones it is mounted above boundary cone C as indicated in Fig. 1.

15 In the form shown in Fig. 2, the unit has three glass parts 20, 21, and 22, all of which may be symmetrical about a vertical axis. The lower glass part 20 has a threaded neck 23 to be received within the fitter 10 and adapted to be threaded down against a gasket 24. This glass part extends upwardly and outwardly as indicated in the drawing and is provided with internal ribbings 25 adapted to diffuse the light, as indicated at A, A'. The upper portion of the glass member 20 is provided with a flange 26 having an annular rib 27 in its upper face 28.

20 Glass member 21 is a refractor and is provided with a suitable prismatic formation to redirect the light somewhat as indicated by the light rays 30 B, B'. It will be noted that refractor 21 is of generally conical shape, that its lower edge rests on the upper face of the lower member 20, and that it is closed at the top 29.

25 The outer envelope 22 of pressed or blown glass, clear or colored, has its lower edge 30 resting on the periphery of the flange 26 of the lower glass member. The parts 22 and 20 are clamped together by C-shaped clamps 31. A spring 32 interposed between the cover glass 22 and the refractor 21 acts to hold the refractor in position so that the glass parts 20, 21, and 22 may form a preassembled unit. The opening in the threaded neck of the lower glass part is somewhat larger than the lamp bulb 16 so that one can remove 45 the glass parts past the lamp bulb.

30 The light distribution of the boundary light shown in Fig. 2 is illustrated by the photometric curve P of Fig. 1. It will be seen that this curve shows a primary beam p projected upwardly at 50 angle of about 7.5°, which is approximately the average gliding angle of airplanes, and that the lower secondary beam S is projected downwardly and outwardly diverging at an angle of about 15° from nadir. This beam of light is in- 55

dicated by the rays A' and is sent out in such a direction as to fall on the surface of the boundary cone C to illuminate this cone and facilitate observation by the aviator.

5. In the form of construction shown in Fig. 3, the lower glass member 20' is made the same as the glass member 20 except that it is provided with externally reflecting prisms 25' which return some of the downwardly directed light upwardly to be redirected by the upper glass member 21 thereby reinforcing the primary beam.

In the construction shown in Fig. 4, the outer envelope 22' is provided with internal prisms 33 designed to further concentrate the light and with 10 shallow vertical flutes 34 to give some lateral diffusion and better appearance to the globe without materially affecting the vertical distribution.

The unit of the type shown in Figs. 2 and 4 has a very wide vertical angle of acceptance. All 20 the light emitted by the lamp is effectively utilized and inasmuch as the refractor 21 extends a very substantial distance below the light source L, the largest proportion of the emitted light on the lamp is handled by this refractor and redirected 25 into the desired direction.

In the form of unit shown in Fig. 5 the outer protective envelope is dispensed with. The outer surface of the refractor 40 is smooth and the inner prisms 41 are designed to direct the light outwardly and upwardly at an angle of approximately 30 7.5°. The lower glass member 42 is provided with external reflecting prisms 43 adapted to return most of the light upwardly as indicated by the arrows D, D'.

35. What is claimed is:

1. An airport boundary light adapted to function as a signal to an aviator and comprising a support carrying an upwardly extending light

source and an upwardly and outwardly flaring light transmitting member for transmitting the lower portion of the downwardly emitted light into a secondary diverging beam, and a refractor whose lower edge rests on the lower transmitting member 5 adjacent the periphery thereof, the refractor having annular prisms extending from below the horizontal plane of the light source substantially to zenith, the prisms accepting all the light emitted above the transmitting member and being 10 adapted to concentrate the light into an intensive primary beam with its angle of maximum intensity inclined slightly upwardly above the horizontal for signalling purposes to the aviator.

2. An airport boundary light as claimed in claim 15 1, wherein a protective envelope rests on the periphery of the lower light transmitting member and covers the entire refractor.

3. An airport boundary light adapted to function as a signal to an aviator and comprising a 20 support carrying an upwardly extending light source and an upwardly and outwardly flaring light transmitting member for transmitting a portion of the downwardly emitted light into a secondary diverging beam for illuminating a 25 boundary cone below the support, and a refractor of generally conical shape closed at the top and having its lower edge resting on the lower transmitting member adjacent the periphery thereof, the refractor having annular prisms accepting 30 light through an angle substantially greater than 90° measured from zenith to concentrate the light into an intensive primary beam with its angle of maximum intensity inclined slightly upwardly above the horizontal to provide a continuous 35 bright signal while gliding to a landing in the field of the airport.
